UNITED STATES PATENT OFFICE.

JAMES H. JONES, OF CLEVELAND, OHIO.

RUG AND CARPET CLEANING MACHINE.

1,314,813.

Specification of Letters Patent.

Patented Sept. 2, 1919.

Application filed September 7, 1915. Serial No. 49,174.

To all whom it may concern:

Be it known that I, JAMES H. JONES, a citizen of the United States, and resident of Cleveland, in the county of Cuyahoga and State of Ohio, have invented certain new and useful Improvements in Rug and Carpet Cleaning Machines, of which I hereby declare the following to be a full, clear, and exact description, such as will enable others skilled in the art to which it appertains to make and use the same.

The objects of the invention are to provide a rug or carpet beating machine having the following features of novelty and improvement.

It is so constructed as to permit the cleaning of large and small rugs and to perform the operation thoroughly in a machine not larger than would ordinarily be required to clean a small rug.

The invention includes the combination and arrangement of parts and construction of details hereinafter described, shown in the accompanying drawings and specifically pointed out in the claims.

In the accompanying drawings Figure 1 is a front elevation of the machine; Fig. 2 is a longitudinal section thereof on line 2, Fig. 5; Fig. 2^a is a transverse section of the beater shaft and sleeve thereon; Fig. 3 is an end elevation of the machine showing the operating mechanism therefor; Fig. 4 is an elevation of the opposite end of the machine; Fig. 5 is a transverse section of the machine on line 5, Fig. 1; Fig. 6 is a perspective of the apertured grating over which the rug is beaten. Fig. 7 is a transverse section thereof enlarged; Figs. 8 and 9 are sectional views of the clamping and securing means for the respective extremities of the spring guard rods, Figs. 10 and 11 are a plan and transverse section respectively showing the device for releasing the friction roll, from the friction disk; Fig. 12 is a longitudinal section through the beater shaft; Fig. 13 is an enlarged portion thereof; Fig. 14 is a side elevation of operating gears showing the cam clutch in the engaging position.

In these views A is a hollow casing in which the working parts are assembled; B is the beater shaft which passes longitudinally through the machine and is provided preferably with sectional sleeves B' upon which the beating straps B² are secured and arranged at different angles to secure a con-

tinual unbroken succession of blows upon the carpet, as the shaft and sleeves revolve.

The sleeves B' are loose upon the shaft and spaced adjustable flange rings B⁴, B⁴ which are mounted upon the sleeves are connected by means of spaced rods B⁵, B⁵ underneath which the ends of the beating straps are inserted, so that by rotating the flange rings upon the sleeves the straps can be wound up upon the sleeves to increase or lessen at will the length of the outer and striking portions as shown in Fig. 2^a at b.

The flanges are secured in any position upon sleeves B', preferably by means of set screws B³.

Clutches B⁶, B⁶ connect the several sleeve sections with the shaft B, so that either section can be disconnected from the shaft to stop the action of the beaters at any time. Levers B⁷ operate these clutches. Each clutch member B⁸ engages with a complementary sleeve clutch member B⁷ detachably secured upon an inner sleeve B⁸, upon which one end of the sleeve B' is rigidly secured, so that when the clutch members are in engagement, motion will be transmitted to the sleeve B'.

A key way or slot B⁹ in the shaft and an elongated key B¹⁰ in the clutch permit longitudinal movement of the clutch member B⁶.

The rugs or carpets while being beaten pass over the apertured grid or grating C which serves as a supporting platform through which extend the inlet perforations c, c, formed in a depressed partition c', leading to the vacuum creating apparatus.

These perforations communicate directly with the exhaust passage C¹⁰ in the grating C.

The exhaust passage C¹⁰ communicates with an inclined exhaust pipe C² which leads to a powerful suction device or exhaust fan C³ through which the dust is removed from the inlet openings.

A hand hole C⁴ and cover C⁵ therefor facilitate the removal of sand or accumulations of any kind which remain in the tube C².

The apertured grating C is depressed at its longitudinal edges at C⁶, C⁷, and is correspondingly raised on the upper surface and is provided with a longitudinal slot C⁸ for the entrance of clean air upon each side of the rows of inlet openings c, c.

110

Passages or chambers C', C' for the introduction of clean air inclose the longitudinal slots C⁸ in the raised portion of the apertured platform and provide a constant supply 5 of fresh air from beneath the rug, which passes upward through the longitudinal slots and rug, and is drawn down through the inlet perforations c, c, thus preventing the dusty air from the casing from passing through the rug.

The chambers pass through one end wall of the casing as shown in Fig. 4.

Discharge openings C⁹, C⁹, are also provided giving plentiful opportunity for the escape of the heavier dust or sand as it falls from the rugs, which travel face downward over the apertured platform C. These openings are preferably arranged intermediate of the inlet openings c, and one or both edges 20 of the platform, exterior to the passages C'.

Such material as passes through these openings C⁹ falls directly into the cavity of the casing from whence it can be removed at pleasure.

25 In use the rugs are fed into the machine through a lateral opening D' in the front wall thereof, and thence over a horizontal screen D which is vertically adjustable by means of cams D², D² upon a rotatable longitudinal shaft D³, operated by the lever D⁴. The rug is drawn over the polished metal edge D⁵.

The rugs are propelled by the combined feeding and beating roll E mounted upon a rotatable shaft E' which propels and beats the rugs to remove the coarser dust and dirt therefrom before they pass over the apertured platform C and underneath the beating straps B², B². This roll comprises an elastic brush formed preferably of non metallic fibers or bristles which propel the rug without wearing or tearing its back. Any dirt or dust elevated by this roll is drawn through a lateral opening E² and passes 40 through a conducting pipe E³ to a second blower E⁴, shown in Fig. 1.

Transverse spring guard rods or keepers F, F, are removably attached at intervals to the sides of the casing and lie over the rug in its passage to prevent it from winding up over the propelling roll and to cause it to lie smoothly in contact with the grating C while under the action of the beating straps.

55 These guard rods are curved at the front end to avoid the shaft E' at F' and at their rear ends are doubled upon themselves at F² to increase their elasticity so that they will not become broken under the repeated action of the beating straps, and at their extremities they are provided with screw threaded ferrules F³, F³, see Figs. 8 and 9, which are screwed into the frame, and reinforced. In this manner the rods are protected from breaking where the screw

threads join the casing, when they are caused to vibrate severely by the action of the beating straps.

A final sweeping roll is shown at G mounted upon a longitudinal shaft G' at the rear of the apertured platform.

This roll sweeps and slightly lifts the rug from below as it is passing over a second grating H and the fibers or bristles G of this roll are arranged in oppositely positioned rows so as to exert an intermittent sweeping and propelling force upon the rug and to remove the hair or thread from the nap of the rug, which could not be removed by the action of the beaters and vacuum alone.

It will be observed that when the rug passes over the depressed edges C⁶ C⁷ of the grating C it will sag from want of support at these points and hence will become more flexible to assist the action of the beaters in removing the dust therefrom.

The same action takes place when the rug passes over the depressed partition c' and inlet perforations c, c.

The shafts for operating the propelling roll and the beaters are rotated by means of mechanism shown in Figs. 1 and 3, positioned exterior to one end of the casing.

Here L is a band or belt wheel mounted upon the driving shaft G' upon which the brushing roll G is mounted. L' and L² are spur gears mounted upon the shafts B and G' respectively and driving the beater shaft B at a predetermined rate of speed greater than that of the elastic propelling roll.

Upon the beater shaft B is shown a disk J engaged by a friction roll J' which is mounted upon a transverse shaft J² and a worm J³, upon this shaft engages with a worm-wheel J⁴ upon the shaft E' of the propelling roll E. In this manner the rate of speed of the propelling roll is much reduced below that of the driving shaft and beaters.

The friction roll J' can be made to travel diametrically across the disk J to vary the speed of the worm shaft by means of the nut J⁷ operatively connected to J' which travels upon a screw threaded shaft J⁸ parallel to the worm shaft.

A hand wheel J⁶ operates the screw threaded shaft and nut. Means are also shown in Figs. 3, 10 and 11 for throwing the friction roll J' so that the propelling roll will cease operating.

This comprises a hinged member or rock arm K upon which one end of the worm shaft is mounted and a rotatable wedge or cam sleeve K' having an inclined edge K² which engages an inclined face upon a block K³ secured to the end of the casing. A bell crank lever K⁴ and link K⁵ rotate this cam sleeve. A spring K⁶ above the cam sleeve is then raised and in turn engages one end of the hinged member K and depresses the

other end carrying the friction roll and worm, so that the friction roll will make contact with its driving disk.

The action of the spring k^6 makes the contact resilient in effect.

5 In Figs. 1, 4 and 5 is shown a transverse slot M in the end of the casing, opposite the driving mechanism.

This slot communicates at its ends with 10 the longitudinal slot D' in the front wall of the machine, and the longitudinal opening M' in the rear wall of the machine.

This slot permits larger rugs to be beaten than could otherwise be gotten into the machine, since when one-half is beaten the rug 15 can be turned around after leaving the machine and the other half beaten, permitting one-half of the rug to extend beyond the machine.

20 To support the upper portion of the end of the casing opposite the gearing horizontally extended frames M^2 , M^2 , are positioned as shown in Figs. 1, 2 and 4, which retain the upper portion of the casing at this end 25 in spaced relationship to the lower portion, and the opposite end wall being integral forms a rigid support at that end.

Having described the invention what I 30 claim as new and desire to secure by Letters Patent is:

1. In a rug beating machine, exhaust mechanism, a hollow casing, a platform grating over which the rug passes, said grating having an upwardly curved portion on 35 its upper surface and depressed portions and provided with inlet perforations in the elevated portion, an adjustable screen over which the rug passes to the grating, an elastic feeding roll adjacent to said grating, a 40 beater shaft and flexible beaters thereon, a rotatable brush engaging the lower surface of the rug at the outlet side of said grating and means for retaining the rug in contact with the surface of said grating.

45 2. In combination in a rug beating machine, exhaust mechanism, a casing, a longitudinal grating therein having an upwardly curved upper surface and provided with perforations leading to said exhaust there- 50 through and over which said rug passes, an adjustable screen at the inlet side of said grating over which said rug passes, an elastic propelling roll adjacent to said screen, flexible beaters in said casing and means for ro- 55 tating the same, to engage said rug while passing over said grating, a second grating, and a brush underneath the same operating to remove material not removed by said beaters.

60 3. In a rug beating machine in combination, a casing having a longitudinal opening in its side, exhaust mechanism, a vertically adjustable screen in said opening said screen having a smooth metal inner edge, an elastic propelling roll over said screen, exhaust

producing mechanism, a passage leading from said roll to said exhaust mechanism, a rug supporting apertured platform over which said rug passes, said platform having depressed portions permitting the rug to sag 70 thereover and provided with inlet perforations leading to said exhaust, revolving beaters operating upon the rug while upon the platform, protecting guards for the rug, a grating following the apertured platform, 75 and a sweeping device underneath said grating.

4. In a rug beating machine in combination, a casing and exhaust mechanism, said casing having a longitudinal opening in its 80 side for the introduction of the rug, an elastic propelling roll, an apertured platform over which said rug passes, flexible beaters thereover, a grating following said platform over which said beaters operate, sweeping 85 devices underneath said grating and means for operating the said propelling roll, beaters and sweeping devices at predetermined relative rates of speed.

5. In a rug beating machine, in combination a casing, an exhaust mechanism, a screen over which the rug is fed to the machine, an elastic propelling means thereover, an apertured platform over which the rug travels, said platform provided with 95 depressed inlet perforations communicating with said exhaust mechanism, flexible beaters over said platform and a brushing device for completing the cleaning of the rug and operating upon the finished surface thereof. 100

6. In a rug beating machine a casing, exhaust mechanism, a propelling means for the rug, a screen thereunder, an apertured platform having depressed edges adjacent to said screen and provided with an opening 105 leading to said exhaust mechanism, a depressed and perforated partition in said opening, a chamber for fresh air extending through the wall of said casing and communicating with the apertures in said platform, beating devices over said platform and means for operating said propelling means and beating devices, substantially as described. 110

7. In a rug beating machine, a casing, an apertured platform therein comprising a grating having series of marginal openings and an exhaust opening, a depressed partition in said exhaust opening, said partition provided with perforations, and said platform provided with openings for fresh air adjacent to said exhaust openings. 115

8. In a rug beating machine, a casing, an apertured platform therein comprising a grating having series of marginal openings and an exhaust opening, a depressed partition in said exhaust opening, said partition provided with perforations, said platform provided with openings for fresh air adjacent to said exhaust openings and a chamber 120

125

through which said fresh air openings communicate with the air exterior to the machine.

9. In a rug beating machine, an apertured platform, said platform having an elevated portion and a depressed portion over which the rug passes, and also provided with an exhaust opening or passage extending through the elevated portion and a depressed partition in said exhaust opening said partition having perforations communicating with said exhaust passage.

10. In a rug beating machine, in combination, a casing and exhaust mechanism, a rotatable propelling means, an apertured platform having an exhaust passage over which the rug travels, a rotatable beating device, over said platform, a rotatable brushing device underneath said rug, means for rotating said brushing and beating devices and means for rotating said propelling device, and means for controlling the rate of speed of the propelling device and for reversing its direction of movement substantially as described.

11. In a rug beating machine, in combination, a rug beating device, comprising a rotatable shaft, a sleeve rotatable thereon, a series of flexible straps secured to said sleeve, flanges on said shaft, parallel rods secured to said flanges and passing over and spaced from said sleeve underneath which said straps pass, and means for adjustably securing said flanges upon said sleeves to adjust the length of the protruding portion of said straps.

12. The combination with a rotatable shaft, and sleeves thereon, of clutch devices for operatively connecting said sleeves and shaft, flanges adjustably secured upon said

sleeves, rods connecting said flanges and spaced from said sleeves, and straps secured at one end to said sleeves and having their free ends extending underneath the rods.

13. In a rug beating machine, the combination with a casing having walls, a propelling roll and a platform having an exhaust opening, of guard rods secured transversely at their ends to said casing walls, said rods provided with doubled portions adjacent one end thereof.

14. In a rug beating machine, the combination with a casing, a propelling roll and a platform having an exhaust opening, of transverse guard rods secured in said casing over said platform, said rods having looped portions and reinforced extremities.

15. In a rug beating machine, the combination with a casing, a propelling roll and a platform having an exhaust opening, of transverse guard rods secured in said casing over said platform, and having looped portions and reinforced extremities, comprising internally screw threaded ferrules to which said rods are attached, said ferrules attached to said casing.

16. The combination with the casing of a rug beating machine, said casing provided with an integral end wall and having the opposite end wall and the side walls horizontally divided, and a frame work comprising horizontally extending members supporting the upper portion of said horizontally divided end wall.

In testimony whereof, I hereunto set my hand this 9th day of August, 1915.

JAMES H. JONES.

In presence of—

Wm. M. MONROE,
RALPH W. JEREMIAH.
